JAMES DUVALL, OF CAMAS, WASHINGTON.

PAPER-BAG MACHINE.

1,249,354.

Specification of Letters Patent. Patented Dec. 11, 1917.

Application filed May 31, 1916. Serial No. 100,808.

To all whom it may concern:

Be it known that I, JAMES DUVALL, a citizen of the United States, and a resident of Camas, county of Clarke, and State of

5 Washington, have invented certain new and useful Improvements in Paper-Bag Machines, of which the following is a specification.

My invention relates to paper bag machines wherein a width of paper is folded longitudinally into a continuous tube from which the bags are made and has for its principal object an improved method of severing this paper tube into blanks at proper intervals. In most of the bag machines in common use a striker arm revolves for this purpose whose path is outside of the frame of the machine, thus taking up much more floor space than necessary and adding a 15 danger element to the machine which calls for a guard that takes up more space. The most serious objection however to the usual type of cut-off is the necessity of altering the tension on the tube just as it is to be severed. The tube must be slackened up for an instant, which is done by pinch rolls traveling slower than the draw rolls which feed the tube to the machine. This slackening up movement for the purpose of severance 20 is a source of much trouble, not only limiting the speed at which the bag machine can be run, but unless the adjustments are very carefully made and maintained, the tube is torn or mutilated and the machine plugged, 25 resulting in much loss of time and product. In overcoming these defects I have designed a striker arm movement which travels in the path of the paper tube, wholly inside of the frame of the bag machine and no "slackening" 30 of the tube is necessary to its successful operation, thus eliminating the probability of "plugging." The striker arm being wholly inside the frame, a bag machine so equipped will take up about twenty-five per cent. 35 less floor space and the construction of the frame itself will be simplified. All danger from a swinging arm outside the frame and any necessity for a guard is removed. I have also provided a swinging means for 40 holding the top bed knife, admitting of perfect accessibility when it is desired to adjust or sharpen it or the former and the former knife. In conjunction with the cut-off arm, "delivery" rolls have been given 45 an intermittent movement which keeps the tension on the tube uniform at the time of

severance. By omitting the usual "pinch" rolls driven at half speed I have simplified the machine very materially, which enables it to be run at an increased speed. 60

The accompanying drawings show only so much of the bag machine as is necessary to a full and exact description of my improvements. Figure 1 is a plan. Fig. 2 is a side elevation. Fig. 3 shows in perspective the delivery rolls 7 and 8, with actuating cam and rollers 2 and 3 of top roll. Fig. 4 is a plan of cam 2. Fig. 5 is side view of same showing the two disks composing cam 2, which allows adjustment. Fig. 6 is side elevation of cut-off gear bracket 30, showing eccentric bushing 27. Fig. 7 shows diagrammatically in side elevation all that is necessary to follow the passage of the paper tube through the machine in its relation to the cut-off mechanism. 75

The paper tube, folded longitudinally around former 20, is fed to the machine by the draw rolls 23 and 24, Figs. 2 and 7. The top side of the bag is on top of the former 80 and passes under bed knife 19; the underside of the bag is underneath the former and passes underneath the serrated forward edge of the former which is termed the former knife. As the tube advances it passes on to 85 the lower guide table 11 and the upper guide fingers 12 and 13, Fig. 2, rest firmly on the top side of the tube and prevent it from raising up too much when struck by the cut-off bar 16 on its up stroke. They also act as 90 guides to insure the alinement of the tube. The draw rolls 23 and 24 feed the tube continuously and the forward end of the tube is engaged by the "delivery" or "pinch" rolls 95 7 and 8, which have the same peripheral speed as the draw rolls 23 and 24. This keeps the tension on the tube uniform and there is no "slackening" of the tube to facilitate its severance, the tube being held taut at all times. When the proper length of tube 100 has passed through the machine as described, the forward end being engaged by pinch rolls 7 and 8, the tube is severed by the striker bar 16, Figs. 1 and 7, moving upward and sharply forcing the bottom and 105 top sides of the tube against the serrated knives 20 and 19 respectively. The severed forward section of the tube is immediately forwarded by pinch rolls 7 and 8 to the nip between bottom forming rolls 1 and 28, 110 which have a higher peripheral speed than rolls 7, 8, 23 and 24. Just as the rolls 1 and

28 engage the forward end of the severed bag blank, the cam 2, Fig. 3, pushes down on roller 3 of arm 4, slightly turning shaft 4^a, and raising arms 5 and 6 carrying the top pinch roll 7, thus releasing the severed bag blank which is free to be drawn rapidly forward by the bottom forming rolls 1 and 28. A spring 10, Figs. 1 and 2, attached to the frame and to the top roll 7 tends to pull the 10 pinch rolls together whenever the cam is inoperative, as when the roller 3 is in recess 9 of cam 2. It is apparent that the striker or cut-off arm 16 must get below the level of the oncoming tube before it reaches the nip 15 of rolls 7 and 8, and to accomplish this, in the arrangement set forth in the drawings, I have shown two scroll gears 14 and 15, which impart a fast and a slow movement to the arm 16 through one revolution. In Fig. 20 7 the large diameter of driving scroll gear 15 is shown in engagement with small diameter of driven scroll gear 14, to which the striker bar is attached,—just before the bar in its upward movement, is forced against 25 the paper tube. This gives the bar 16 its fastest movement just at the time of severing the tube and the movement of the bar continues to be rapid while it is above the level of the tube, then it slows down while underneath, the small diameter of the driving scroll gear 15 being in engagement with the large diameter of the cut-off gear 14. This gives the tube time to pass over to the pinch rolls 7 and 8. Just before the striker reaches 30 the tube on its up stroke, the speed increases and the tube is severed while the bar is moving rapidly. While this type of gear is useful for some lengths and weights of bags, especially those made of heavy weight paper, plain spur gears will work equally well with others and are to be preferred when the adjustments can be made to use them. It will be noted that this striker bar 16 rotates wholly inside of the frame of the 40 machine and that it travels in the path of the paper tube and with it, severing the blank while moving with the paper tube, and thus not subjecting it to the shock of striking against the direction of travel which is the usual way and which necessitates slackening the tube before it can be properly cut and cleanly severed. A means must be provided for taking up the wear of the cut off gears 45 14 and 15 so that they may be maintained in perfect mesh to avoid any back lash. The gear 14 carrying the striker bar 16, is journaled in an eccentric bushing 27, Fig. 6, in gear bracket 30. When the gears need adjustment lock nut 33 is unscrewed, releasing bushing 27, which is turned until the wear is taken up and then the locking device is tightened, which holds the bushing and gear 14 firmly in place.

A very valuable feature is to be found in 60 the means for raising the bed knife 19.

Usually this cutting blade is rigidly affixed so that it is a matter of serious delay to get at it for repairs or to remove it in order to examine and repair the former knife 20 underneath it. The bed knife 19 is firmly attached to a holder with arms 17 and 18, Fig. 1, which are mounted on shaft 32, the ends of which rest in the split clamp bearings 21 and 22. The knife 19 is brought into its proper position and then the clamps 75 21 and 22 are tightened so that arms 17 and 18 are held firmly in place. When it is desired to examine or repair either bed knife 19 or former knife 20, the clamps 21 and 22 are loosened sufficiently and the bed knife 80 swung upward out of the way and the necessary repairs made with the least possible delay.

In addition to the top guide fingers 12 and 13 and bottom guide plate 11, Fig. 1, it is often necessary to adjust the pinch rolls 7 and 8 so that the severed blank will feed properly to the cylinder section or bottom forming rolls 1 and 28. To effect this the bottom pinch roll 8 is mounted in adjustable 90 journals so that its face may be skewed slightly out of alignment with the top roll 7, either forward or back, dependent upon the direction in which it is desired to guide the paper tube. In Figs. 3, 4 and 5 it is apparent how the action of the cam 2 on the roller 3 may be varied in time by adjusting the disks composing the cam in their relation to each other so as to shorten up the recess 9.

I claim,—

1. In a machine for making paper bags, in combination with means for folding the paper longitudinally into a tube and draw rolls to feed the same, of a striker arm which revolves wholly inside the frame of the machine and two adjustable pinch rolls movable toward and away from each other, located just forward of the path of rotation of the striker arm.

2. In a machine for making paper bags, in combination with means for folding the paper longitudinally into a tube and draw rolls to feed the same, of a striker arm which revolves wholly inside the frame of the machine, two adjustable pinch rolls movable 110 toward and away from each other located just forward of the path of rotation of the striker arm and two bottom forming rolls which engage the severed bag blank just as it is released by the separation of the pinch 115 rolls.

3. In a paper bag machine in combination with means for folding the paper into a tube and draw rolls to feed the same, of means to sever the paper tube into blanks, 125 and means for holding the tube taut at the time of severance comprising two pinch rolls one on top of the other, the top roll being journaled at each end in a carrying arm, a rocker shaft to which the arms are at- 130

tached, a rocker arm attached to said rocker shaft, an adjustable cam in engagement with said rocker arm to vary the period of engagement between the top and bottom rolls, 5 a spring attached to the top pinch roll carrying arm and to the frame, tending to pull the pinch rolls together at all times.

4. In a paper bag machine of the type described two pinch rolls, one on top of the 10 other, a rocker shaft, a rocker arm, carrying arms supporting the top roll, an adjustable cam which engages the rocker arm and moves top roll away from bottom roll at

proper intervals, a spring attached to top roll which tends to pull it toward bottom roll, adjustable bearings in which bottom roll is journaled, so that its axis may be thrown out of alinement with that of the top roll, and two bottom forming rolls which engage the severed blank just as it is released 15 by the pinch rolls. 20
